UNITED STATES PATENT OFFICE.

THEODORE W. COOK, OF PHILADELPHIA, PENNSYLVANIA, ASSIGNOR OF ONE-HALF TO
HERBERT B. PAINTER, OF PHILADELPHIA, PENNSYLVANIA.

GUN-CLEANING ROD.

1,080,672.

Specification of Letters Patent. Patented Dec. 9, 1913.

Application filed February 14, 1913. Serial No. 748,353.

To all whom it may concern:

Be it known that I, THEODORE W. COOK, a citizen of the United States, residing at Philadelphia, in the county of Philadelphia and State of Pennsylvania, have invented certain new and useful Improvements in Gun-Cleaning Rods, of which the following is a specification.

10 My invention relates to a gun cleaning rod, that is to say, to a device adapted for use in connection with a cleaning rag for removing the detritus from the interior of gun barrels.

The principal object of my invention is to provide a simple, durable and efficient device adapted to hold and maintain a rag which is reciprocated within the gun barrel to clean the same and which is so constructed and arranged as to securely hold the rag which is merely wrapped about the rod and to maintain the rag free from folds and creases during the reciprocatory movements in the cleaning operation.

The nature and characteristic features of my invention will be more readily understood from the following description, taken in connection with the accompanying drawings forming part hereof, in which—

Figure 1 is a view, partly in elevation and partly in section, showing the device of my invention with the cleaning rag mounted thereon and in operative relationship to the gun barrel; Fig. 2 is an elevational view of the end of a gun cleaning rod embodying the main features of my present invention, the same being shown detached and with the rag removed; Figs. 3 and 4 are transverse sections of the rod taken respectively on the lines 3—3 and 4—4 of Fig. 2; and Figs. 5 and 6 are views similar respectively to Figs. 3 and 4, but of a modified form of my invention.

Referring to the drawings, in the particular embodiment of my invention therein shown, 7 is a round rod of a diameter smaller than the bore of the gun to be cleaned. The rod 7 is preferably made of steel, brass or other durable material preferably softer than the material of which the gun barrel is made, and the device constituting my present invention is preferably integrally formed on the rod near one end thereof. This device as shown comprises a central portion 8 of an external diameter preferably smaller than that of the rod 7 and having outer inclined peripheral sur-

faces 9 and 10. From this central portion 8 on either side thereof are arranged two groups 11 and 12 respectively of ratchet-like prongs or teeth 13 and 14, the prongs 13 of group 11 being all disposed in the one direction away from the central portion 8 and the prongs 14 of the other group 12 being all disposed in the opposite direction away from said central portion 8. The preferred manner of forming the prongs 13 and 14 on the rod 7 consists in machining the said round rod down to a square cross section, and notching the corner edges of the square section to form said prongs or teeth 13 disposed in a direction pointing away from the central portion 8. The square section from which the teeth in one group is formed is preferably arranged with its faces at angles of 45° to the faces of the square section from which the teeth in the other group is formed. In the forms shown in Figs. 2, 3 and 4 the notches in the corner edges of the square section are so formed as to have the resultant base surfaces 16 flat, inclined, and also at angles of 45° to the adjacent flat surfaces 15 of the square section from which the notches are cut, while in the form shown in Figs. 5 and 6 the same effect is obtained by turning the notches on the previously squared section so that the surfaces 16 resulting from the formation of said notches are conical in shape as will be readily understood from a consideration of Figs. 5 and 6, reference being also had to Fig. 2, the appearance of which is substantially similar to the modified form shown in Figs. 5 and 6. The faces 17 of the prongs or teeth are preferably undercut as clearly shown in Fig. 2 of the drawings.

In the use of the device the rag 20, which is an oblong piece of the ordinary cleaning cloth preferably made shorter than the longitudinal extent of the pronged portion of the rod 7, is merely wrapped around said 100 pronged portion, and when the same is inserted within the gun barrel 21 and moved in one direction the teeth of one group of prongs will firmly hold that portion of the rag which is in engagement therewith, and 105 the other portion of the rag will slide over the teeth of the other group of prongs so that the rag will thereby be stretched longitudinally, and when the reversal of the direction of movement of the rod in the cleaning operation takes place, the portion of the rag which was previously firmly held by its 110

group of prongs will now be permitted to slide slightly over said group, the other portion of the rag being meanwhile held firmly by its group of prongs, so that the more the 5 rod and its associated rag is reciprocated within the gun barrel the more efficiently the rag will be longitudinally stretched and freed from lumps and creases.

It will be seen that there is thus provided 10 a simple, durable and inexpensive form of cleaning rod which has been found to be extremely efficient in operation, it being only necessary to wrap the rag around the pronged portion of the rod and it is then 15 ready for use, the arrangement of the prongs being such that the retention of the rag in a smooth uniform condition is at all times assured.

Having thus described the nature and 20 characteristic features of my invention, what I claim as new and desire to secure by Letters Patent is:—

1. A gun cleaning device comprising a 25 rod having a plurality of prongs around which a rag is adapted to be wrapped, said prongs being arranged in two groups, one on each side of an intermediate portion, and all of the prongs in each group being inclined in a direction away from said intermediate portion.

2. A gun cleaning device comprising a 30 rod having a plurality of prongs integrally formed therein, and a rag adapted to be wrapped about said prongs, said prongs being arranged in two groups, one on each side of an intermediate portion, and all of the prongs in each group being inclined in a direction away from said intermediate portion.

3. A gun cleaning device comprising a 40 round rod having a plurality of rigid prongs at one portion, said prongs being arranged in two groups, one on each side of an intermediate portion, and all of the prongs in each group being inclined in a direction away from said intermediate portion. 45

4. A gun cleaning device comprising a 50 round rod having a plurality of rigid prongs at one portion, said prongs being arranged in two groups, one on each side of an intermediate portion, and all of the prongs in each group being inclined in a direction away from said intermediate portion, said prongs being formed by reducing the rod to a square cross-section and notching the corners of said section. 55

5. A gun cleaning device comprising a 60 round rod having a plurality of rigid prongs at one portion, said prongs being arranged in two groups, one on each side of an intermediate portion, and all of the prongs in each group being inclined in a direction away from said intermediate portion, said prongs being formed by reducing the rod to a square cross-section and notching the corners of said section, and the faces of the section from which one group of prongs is formed being at an angle of 45° to the faces of the section from which the other group of prongs is formed. 65

In testimony whereof, I have hereunto 70 signed my name in the presence of two witnesses.

THEODORE W. COOK.
